UNITED STATES PATENT OFFICE.

WILLIAM E. SOMERVILLE, OF COAL CITY, ILLINOIS.

ENDLESS LOOP OR GROMMET.

Application filed June 23, 1922. Serial No. 570,472.

To all whom it may concern:

Be it known that I, WILLIAM E. SOMERVILLE, a citizen of the United States, residing at Coal City, in the county of Grundy 5 and State of Illinois, have invented certain new and useful Improvements in Endless Loops or Grommets, of which the following is a specification.

This invention relates to improvements in endless loops or grommets, particularly adapted, though not necessarily limited, in its use in tire construction and for barrel hoops, slings, or for any other purpose of which an endless loop or grommet of this 15 character may be employed, and one of the objects of the invention is to provide an improved article of this character constructed from an endless piece of wire, cable, individual wire, rope or the like.

20 A further object is to provide an improved article or device of this character formed from a single piece of wire or the like, a portion of the wire constituting a core about which the remaining portion of 25 the wire is wrapped or laid, the extremity of the outer or last strand or wrap being secured to the extremity or end of the core wire so that there will be formed an endless loop, the strand and core of which is 30 also endless, with the result that when the loop is stretched to its limit there will be no slipping of the strands or yielding of the body of the loop.

To the attainment of these ends and the 35 accomplishment of other new and useful objects as will appear, the invention consists in the features of novelty in substantially the construction, combination and arrangement of the several parts hereinafter 40 more fully described and claimed and shown in the accompanying drawing illustrating this invention and in which—

Figure 1 is a view of the completed loop or grommet.

45 Figure 2 is a detail view showing the manner of securing the end of the last strand or wrap to the end of the core.

Figure 3 is an enlarged detail elevation of a portion of the completed loop or grommet.

50 Figure 4 is an enlarged detail sectional view taken on line 4—4 Figure 1.

Figure 5 is a view similar to Figure 3 of a modified form of the invention.

55 Figure 6 is an enlarged sectional view taken on line 6—6 Figure 5.

Figure 7 is a view similar to Figure 3 showing still another modified form of the invention.

Figure 8 is a sectional view taken on line 60 8—8 Figure 7.

The terms wire and strand will be employed throughout the specification and claims for designating the material from which the article is constructed, but it is to be understood that these terms are not 65 to be considered as terms of limitation but are to be construed broadly to mean a single wire, cable, or a plurality of wires or cables, or rope, and the strands may also be of a single wire, cable, a multiplicity of wires, 70 cables, or rope.

Referring more particularly to the drawing the core 10 is formed by a strand of the material shaped to form a loop of the proper diameter. The remaining portion of the 75 wire forming a continuation of the core is wrapped or laid around the core 10 as at 11, the wraps or convolutions of the strand being disposed at any desired or suitable angle and wrapped the desired number of 80 times around the core.

After the wrapping or laying process has been completed the last strand 12 is severed from the supply to produce an end 13, the 85 extremity 14 of which end terminates adjacent the extremity 15 of the core, but on the outside of the loop, while the extremity 15 of the core 10 is embedded or completely housed within the body of the loop.

The next step in the operation of constructing the loop is to separate the strands adjacent the extremity 15 of the core 10, so that access can be had to the end of the core. This end is then drawn through the 95 opening thus formed into a position that the extremity 14 of the end 13 of the strand may be secured thereto, either by brazing, welding, or in any other manner suitable to accomplish that end.

After the extremities 15—16 have been 100 secured together the joint thus formed is forced between the open or separated strands, and the entire loop or grommet is then stretched so as to cause the separated strands to assume their normal positions to 105 completely conceal the joined ends. The loop is further stretched to approximately its elastic limit, thereby forming a permanent set of the loop and this will prevent any further stretching of the loop when in use.

110

With this improved construction it will be manifest that there is provided an endless loop or grommet constructed from an endless wire, a portion of the wire constituting a core therefor. In Figures 1 and 4 of the drawing the loop or grommet is shown as being constructed from a single wire.

In Figures 5 and 6 there is illustrated what is known as a nineteen wire strand construction, there being six strands 16 wrapped about the core 17, and twelve strands 18 wrapped about the strands 16. In constructing this form of loop or grommet, and in order that the last strands or 15 wraps will form a smooth or regular outer surface, so as to prevent the outer strands from being placed within the grooves formed between adjacent strands of the next inner most layer, the angle of the wrap or 20 lay of the outer most strands 18 is changed, so that the strands will assume the positions shown in Figure 6.

In Figures 7 and 8 there is illustrated what is known as a seven wire or seven cable construction each of the strands 19 are formed of seven strands, six of the strands 20 being wrapped about the core strand 21. These strands 19 thus formed are wrapped about the portion 22 which latter constitutes 30 the core and the extremity of the core and the last strands are secured together in the same manner, as described in Figures one to three. Obviously this improved loop or grommet may be constructed of any material suitable for the purpose, the manner 35 of forming the joint between the extremity of the strand being varied according to the nature of the material being employed.

While the preferred forms of the invention have herein been shown and described it is to be understood that various changes may be made in the details of construction and in the combination and arrangement of the several parts, within the scope of the 45 claims without departing from the spirit of this invention.

What is claimed as new is:

1. As an article of manufacture a loop or grommet embodying a core, the body of the 50 loop being formed from a continuation of the core wrapped or laid around the core, the end of the core and the end of the wrapped portion being secured together.
2. As an article of manufacture a loop or 55 grommet embodying a core, the body of the loop being formed from a continuation of the core wrapped or laid around the core, the end of the core and the end of the wrapped portion being secured together, the joint thus formed being embedded within 60 and encompassed by the body strands.
3. As an article of manufacture an end-

less loop or grommet embodying a core and a body portion formed by wrapping or laying a plurality of strands about the core, all 65 of said strands being formed from a single continuous piece of material, the core forming a continuation of the strands, the extremity of the last wrap or lay of the strands and the extremity of the core being 70 secured together.

4. As an article of manufacture an endless loop or grommet embodying a core and a body portion formed by wrapping or laying a plurality of strands about the core, all 75 of said strands being formed from a single continuous piece of material, the core forming a continuation of the strands, the extremity of the last wrap or lay of the strands and the extremity of the core being 80 secured together, the joint thus formed being embedded and concealed within the body portion of the wrap.

5. The method of constructing an endless loop or grommet from a continuous wire 85 which consists in forming a core from one end of the wire, then wrapping or laying the remaining portion of the wire about the core, then separating the strands of the body to gain access to the extremity of the core, 90 then securing the said extremity of the core and the extremity of the last strand together, and there forcing into the body of the loop, the joint thus formed.

6. The method of constructing an endless loop or grommet from a continuous wire which consists in forming a core from one end of the wire, then wrapping or laying the remaining portion of the wire about the core, then separating the strands of the body to gain access to the extremity of the core, then securing the said extremity of the last strand together, and then forcing into the body of the loop, the joint thus formed, and finally stretching the loop to draw the separated strands back into close proximity. 105

7. A re-enforcing ring for automobile tires comprising a continuous wire winding forming a plurality of strands with the ends 110 of the wire joined and surrounded by the other strands.

8. The method of forming re-enforcing rings for automobile tires comprising the continuous winding of wire to form a plurality of strands, joining the ends of the wire to each other, arranging the wires to surround the joint with the continuous strands, and securing the wires in this relation. 115

In testimony whereof I have signed my 120 name to this specification, on this 21st day of June, A. D. 1922.

WILLIAM E. SOMERVILLE.
